UNITED STATES PATENT OFFICE.

PHILIP H. MYERS, OF PHILADELPHIA, PENNSYLVANIA.

SWITCH-LOCK.

1,348,729.

Specification of Letters Patent.

Patented Aug. 3, 1920.

Application filed July 23, 1919. Serial No. 312,717.

To all whom it may concern:

Be it known that I, PHILIP H. MYERS, a citizen of the United States, and a resident of Philadelphia, in the county of Philadelphia and State of Pennsylvania, have invented a new and Improved Switch-Lock, of which the following is a full, clear, and exact description.

This invention relates to a switch lock, and aims to provide a device by means of which when the point of a switch has once been thrown it would be impossible for this point to shift subsequently, unless directly operated by some outside agency.

As it is known at the present time, the usual type of automatic switch, employed more particularly in connection with street railways, is one which is operated by means of electromagnets. The motorman of a car, when operating a switch of this type, usually brings the car to an almost complete stop at a predetermined point in advance of the switch. He then operates his electrical controller so that a certain amount of current is introduced through the motors of the car. At this point the third rail, or trolley wire, is provided with suitable means which act as an agent to supply current through the electromagnets of the switch, resulting in the throw of the switch point to the opposite direction from which the same is stationed at that time.

The above-described apparatus involves the provision of a fairly complicated electrical arrangement to produce these results. It has often occurred, through certain defects in this system, that the front truck of a car has been guided in a certain direction and, subsequent to the passing of such first truck over the switch point, and prior to the entrance of the second truck thereon, the point has been thrown back, resulting, especially when the car is traveling at a fairly high rate of speed, in one, if not both, of the trucks jumping the track, which has caused quite a number of serious accidents, besides tying up traffic and resulting in a proportionate increased expense of operation to the railway company.

I have now constructed a switch which is positive in operation and which may be operated by entirely mechanical means, as well as a switch which embodies certain construction, which makes it absolutely impossible for the point to be thrown without wilful operation on the part of an outside agency.

Reference is had to the accompanying drawings which illustrate one practical embodiment of my invention, in which—

Figure 1 is a plan view of a switch with certain of the housings for the operating and locking mechanisms in section, so as to reveal the underlying structure;

Fig. 2 is a section taken along line 2—2 of Fig. 1 and showing upon the track the front part of a car provided with one convenient form of switch-operating mechanism;

Fig. 3 is a sectional front view taken along line 3—3 of Fig. 1; and

Fig. 4 is a section taken along line 4—4 of Fig. 1 and also showing mounted upon the tracks a car with a switch-operating mechanism similar to that disclosed in Fig. 2.

In all of these views like reference numerals indicate similar parts, and 1 designates the conventional ties upon which rails 2 are mounted. Referring more particularly to Fig. 1, it will be seen that I have disclosed a switch embodying the conventional frog 3 and a movable point 4. The point is positively held or moved by means of a slidable bar 5 which is pivotally secured at one of its ends, as indicated by the reference numeral 6, to the point 4. The outer end of such bar may project into an opening, such as 6', associated with the rails 2 at this point, when the point has been moved so as to provide a straight-away track. The opposite end is pivotally secured as indicated by the reference numeral 7, to a portion approximately intermediate the two extremities of a rocker arm 8. The rocker arm is held so as to be capable of oscillation by means of a link 9 which has its outer end pivotally secured to a fixed portion, such as the tie 1, its opposite end connecting with the rocker arm 8 at the pivot 7.

One of the outer ends of the rocker arm 8 bears against the inner face of one of the rails 2, the opposite end thereof riding inwardly along a wedge surface 10.

Assuming now that it is desired to operate the point 4 by means of an element mounted upon the car, so that it will not be necessary to have a switch attendant; I provide, as clearly shown in Fig. 1, slidable links 11, which are pivotally secured at their outer ends to the extremities of the rocker arm 8 slotted, as indicated by the reference numeral 12, in which slots, pins 13 mounted upon slidable blocks 14 ride.

The blocks 14 are provided with upstand-

ing ears 15, which ears are engaged by means of the slotted ends 16 of a bar 17 which is rotatably mounted upon a fixed base, such as the tie 1.

- 5 Any suitable operating mechanism may be provided for moving the ears 15 and, consequently, projecting the blocks 14, such as, for instance, the device illustrated in Figs. 2 and 4, in which the car is provided with a 10 rocker bar 18 formed with downwardly-extending ends 19. The rails 2 are preferably provided at points adjacent the path of travel of the ears 15 with shallow scooped-out portions 20, by means of which the 15 downwardly-dependant ends 19 of the rocker bar 18 will be moved out of engagement with such ears when the limit of travel of the blocks 14 has been reached.

In operation it will now be appreciated 20 that the switch point might be thrown by any suitable agency in lieu of the links 11 and their operating mechanism, but assuming that the structure shown is employed, it will be appreciated that it will be an easy 25 matter for the operator of a car to depress the required side of the bar 18 so that the downwardly-bent end 19 will ride into the scooped-out portion 20 of the rail 2 and, consequently, engage the ear 15 of the block 14, 30 causing said block to be projected forward. By virtue of the links 11 being connected with the blocks 14, the same will be caused to move with such blocks and result in a moving of the outer ends of the rocker 35 arm 8.

One end of the rocker arm 8 will move downwardly along the face of one of the wedges 10, while the opposite end is rising along the face of the opposite wedge, resulting 40 in a longitudinal shifting of such arm and a consequential pull or push upon the bar 5, causing an opening or closing of the switch point.

As aforesaid, upon the completion of the 45 above-described operation, the downwardly-bent end 19 of the rocker bar 18 will ride out of engagement with the ear 15 by virtue of the shallow scooped-out portion 20 of the rail 2. It will now be understood that it 50 will be absolutely impossible for the point to shift again unless the links 11 are moved, by reason of the wedge surfaces 10; and in connection with this it is pointed out that it would be impossible to even manually 55 shift the point 4 by means of a bar, similar to a crowbar, by virtue of the locking action exerted by such wedge surfaces. On the other hand, an oscillation of the rocker arm 8 about the pivoted end of the link 9 60 is effected with the utmost ease when a push is exerted upon either one or the other of the links 11.

It is to be appreciated that any number of

modifications may be made in connection with the structure of my device within the 65 scope of my claims.

Having thus described my invention, I desire to claim:

1. A switch lock, comprising a switch, including rails, a movable point, a bar secured 70 to such point and adapted to hold or move the same, a rocker arm for shifting such bar, and means associated with the outer ends of the rocker arm for normally preventing any longitudinal movement of said 75 bar.

2. A switch lock, comprising a switch, including rails, a movable point associated with such rails, a bar secured to and adapted to fixedly hold and move such point, a 80 rocker arm secured to the inner end of such bar, and wedges coöperating with the outer ends of such rocker arm.

3. A switch lock, comprising a switch, including rails, a switch point associated with 85 such rails, a bar secured to and adapted to positively hold such point, a link having one of its ends pivotally secured to a fixed point, a rocker arm pivotally secured to the opposite end of such link, the opposite end 90 of such bar being pivotally secured to such rocker arm, and wedge surfaces engaging the outer ends of such rocker arm.

4. A switch lock, comprising a switch, including rails, a switch point associated with 95 such rails, a bar secured to and adapted to positively hold such point, a link having one of its ends pivotally secured to a fixed point, a rocker arm pivotally secured to the opposite end of such link, the opposite end 100 of such bar being pivotally secured to said rocker arm at its point of connection with the link, and wedge surfaces engaging the outer ends of such rocker arm.

5. A switch lock, comprising in combination a switch, including rails, a movable point associated with such rails, a bar having its outer end pivotally secured to such point and being adapted to hold and move the same, a link having one of its ends pivoted 110 upon a fixed point, a rocker arm pivotally secured to the opposite end of such link, the inner end of such bar being pivotally secured to such rocker arm at this latter pivot, wedge surfaces coöperating with the outer 115 ends of such rocker arm, links having their outer ends pivotally secured to the outer ends of the rocker arm, slides blocks provided with ears, the inner ends of the links being secured to such blocks, and a bar rotatably 120 mounted upon a fixed point extending between such blocks, the outer ends of such bar being slotted and encircling said ears.

PHILIP H. MYERS.
